UNITED STATES PATENT OFFICE.

AUGUST THONET, OF VIENNA, AUSTRIA-HUNGARY.

DESIGN FOR A CHAIR.

SPECIFICATION forming part of Design No. 23,065, dated February 13, 1894.

Application filed December 7, 1893. Serial No. 493,048. Term of patent 7 years.

To all whom it may concern:

Be it known that I, AUGUST THONET, a subject of the Emperor of Austria-Hungary, residing at Vienna, Austria-Hungary, have invented and produced a new and original Design for Chairs, of which the following is a specification.

In the accompanying drawing, a perspective view of a chair showing my new design is given.

The leading feature of my design consists of a chair having a rectangular seat, front legs and rear-legs united by X-shaped cross-bars, which rear-legs extend above the seat to form part of the back, a segmental top-bar on the back, a U-shaped piece in the back, the top of which U-shaped piece rests against the center of the segmental top-bar, the ends of the shanks of the U-shaped piece being at the back of the seat a short distance from the upper extension of the rear-legs.

A is the seat, B the legs, C the braces, cross-

ing each other below the seat D, having a bead in the front edge of the seat E, the upper extensions of the rear legs forming the 25 side parts of the back F, a segmental bar forming the top of the back G, the U-shaped bar having its top in contact with the center of the under side of the segmental top bar F of the back and the ends of its shanks at the 30 back of the seat A a short distance from the upper extensions of the rear legs.

Having thus described my invention, I claim as new and desire to secure by Letters Patent—

The design for a chair, substantially as shown and described.

In testimony that I claim the foregoing as my invention I have signed my name in presence of two subscribing witnesses.

AUGUST THONET.

Witnesses:

CARL ANDREAR,
DEAN B. MASON.
